Primary Examiner — Darcey E Gottschalk*Assistant Examiner* — Haley K Schnebele(74) Attorney, Agent, or Firm — Fross Zelnick Lehrman & Sissu, P.C.; Charles T. J. Weigell, Esq.(57) CLAIM

The ornamental design for a fragrance bottle as shown and described.

DESCRIPTION

FIG. 1 is a front perspective view of a fragrance bottle showing my new design;

FIG. 2 is a front view thereof;

FIG. 3 is a back view thereof;

FIG. 4 is a left side view thereof;

FIG. 5 is a right side view thereof; and,

FIG. 6 is a top view thereof.

The broken lines in the figures represent portions of the fragrance bottle that form no part of the claimed design.
